Carpenter, Atty's.

UNITED STATES PATENT OFFICE.

EVERT E. BOBBIT, OF CHICAGO, ILLINOIS.

PRINTING-PRESS JOGGER.

Application filed July 22, 1920. Serial No. 398,241.

To all whom it may concern:

Be it known that I, EVERETT E. BOBBIT, a citizen of the United States, residing in Chicago, in the county of Cook and State of Illinois, have invented a new and useful Improvement in Printing-Press Joggers, of which the following is a specification.

This invention relates in general to printing presses and has more particular reference to the provision of means for insuring accurate placement of the printed sheets upon the press table as they are delivered to it by the fly.

The invention has for its object broadly the provision of accurately and positively operating means for holding the delivered sheets upon the pile as they are deposited by the delivery mechanism.

The invention has for a further object the provision of means for accomplishing this result which will not interfere in any manner with the normal and heretofore usual action of the mechanism for delivering the printed sheets, and which will act to restrain any tendency the sheets may have to follow the delivery mechanism on its returning or idle stroke.

Still another important object of the invention is the provision of means of this character which may be provided as a mere attachment, consisting of a small number of simple parts, adapted for easy installation on printing presses already in use and this without requiring any reformation, replacement or readjustment of the parts of the press, and which may be readily adjusted for operation on sheets of various sizes.

Another object of the invention is the provision of an apparatus of the character described of simple, sturdy construction, the parts of which will not require frequent repair or replacement, and which, being wholly automatic in its action, will not require the constant attention of the press operator.

Numerous other objects and advantages of the invention will be apparent as it is better understood from the following description, which, taken in connection with the accompanying drawings, discloses a preferred embodiment thereof.

Referring to the drawings, Figure 1 is a top plan view of a part of a printing press and showing an apparatus in which my present invention is embodied; 55

Fig. 2 is a side elevation thereof, certain press parts being shown in section;

Fig. 3 is a section on the line 3—3 of Fig. 1;

Fig. 4 is a section on the line 4—4 of Fig. 1; and

Fig. 5 is a front elevation of the operating member.

For the purpose of illustrating my present invention I have shown on the drawings 65 so much of a printing press as is believed necessary to an understanding of it. Reference character 11 represents one of the cross rods or braces of the press frame, reference character 12 a shaft carrying the pulleys or spools 13 for the tapes 14. Reference character 15 indicates the oscillating shaft for the flies 16 adapted to lift the sheets from the tapes and deposit them in a pile upon the press table located between the table rails 75 17. It will be understood that the main fly 16 moves in a counter-clockwise direction (viewing Fig. 2) in its operative stroke and in the reverse direction on its inoperative stroke. 80

In the present instance I provide an auxiliary or oppositely acting fly to insure that the deposited sheets are held against movement with the main fly on its return stroke. While in the present embodiment of the invention it may be considered a mere attachment to the printing press, it can be incorporated as a part of its original construction and in any event co-operates with parts thereof. 85

This auxiliary fly comprises a shaft 18 pivoted in bearing 19 of clamps 21 adapted to be fastened upon the table rails 17. At the end of the shaft at the top of Fig. 1 a spring 22 is provided having one end 23 95 fixed in the adjacent bearing 19 and the other end 24 fixed in a collar 25 locked to the shaft by set screw 26. Fly arms 27 in any appropriate number are mounted on the shaft and locked against independent movement by set screws 28. 100

This auxiliary fly is normally held down

upon the top of the pile of sheets by the spring 22 and means are provided for moving it back in a clockwise direction, viewing Fig. 2, when the main fly is to deposit a sheet upon the pile. This means in the present instance is operated by the main fly. An arcuate member 29 is clamped upon the shaft 15 and in position to engage a latch 31 pivoted upon an arm 32 in turn pivoted at 33 upon a collar 34 clamped about the frame part 11. The tail part of this latch engages the body of the arm when the arcuate member 29 is moving downwardly and rearwardly viewing Fig. 2, causing the arm to move in a clockwise direction during the operative movement of the fly. The arm 32 has an upstanding part 36 pivoted at 37 to a rod 38 which rod extends over above the shaft 18 and is connected with an arm 39 fixed on said shaft 18. The connection between the arm 39 and the rod 38 is through a block 41 having a pivot 42 disposed through the arm 39 so that the parts may move freely in action. A collar 43 is fixed on the rod 38 beyond the block 41 so that when the arm 32 is actuated toward the right viewing Fig. 2, movement of the rod 38 swings the auxiliary fly up and out of the way of the paper on the main fly.

The lifting movement of the auxiliary fly moves in accordance with the movement of the main fly and when the arm 32 is moved back about its pivot 33 sufficiently to permit the arcuate member 29 to clear the latch 31, the spring 22 causes the auxiliary fly to move back quickly into place. This action occurs just as the paper is placed upon the pile and when the main fly moves on its idle stroke the upper end of the arcuate member tilts the latch and passes it so that the parts again assume their normal positions. A fixed stop 44 is provided upon a collar 45 fast on the shaft 18 by set screw 46 which stop 44 is adapted to engage a rod 47 mounted in the bearings 19. A spring stop 48 is provided to prevent too great movement of the arm 32 toward the left, viewing Fig. 2, said stop being positioned upon the collar 34.

It will be noted that the auxiliary fly is out of position at the time each sheet is actually placed on the pile and comes quickly down thereagainst at the moment it is deposited so that it holds the sheet before it has been misplaced through tendency to follow the main fly on its return movement.

It is thought that the invention and many of its attendant advantages will be understood from the foregoing without further description and it will be apparent that various changes may be made in the form, construction and arrangement of the parts without departing from the spirit and scope of the invention or sacrificing all of its material

advantages, the form hereinbefore described being merely a preferred embodiment thereof.

I claim:

1. In a printing press the combination of 70 tapes, a table, a fly for lifting sheets from the tapes and depositing them upon the table, and an auxiliary fly movable opposite to the movement of the first mentioned fly and acting to prevent sheets deposited on 75 said table from following the first mentioned fly in its return movement.

2. In a printing press the combination of 80 tapes, a fly for lifting printed sheets from the tapes and depositing them upon the table, and means controlled by said fly for preventing sheets deposited on said table from following the fly in its return movement.

3. In a printing press the combination 85 of tapes, a table, a fly for lifting printed sheets from the tapes and depositing them upon the table and means movable out of the way by the fly in depositing sheets upon the table for preventing said sheets from 90 following the fly in its return movement.

4. In a printing press the combination of 95 tapes, a table, a fly for lifting printed sheets from the tapes and depositing them upon the table, means movable out of the way of the fly in depositing sheets upon the table for preventing said sheets from following the fly in its return movement and means normally pressing such first mentioned means upon the pile of accumulated 100 printed sheets on the table.

5. In a printing press the combination of 105 tapes, a table, a fly for lifting printed sheets from the tapes and depositing them on the table, and means having parts disposed in the path of movement of parts of said fly for preventing printed sheets moving with the fly on its return movement, said parts of said means and said parts of said fly having latching engagement when the fly is moving 110 in one direction.

6. In a printing press the combination of 115 tapes, a table, a fly for lifting printed sheets from the tapes and depositing them on the table, and means having parts disposed in the path of movement of parts of said fly for preventing printed sheets moving with the fly on its return movement, said parts of said means and said parts of said fly having latching engagement when said fly is moving 120 on its operative stroke.

7. In a printing press the combination of 125 tapes, a table, a fly for lifting sheets from the tapes and depositing them on the table and an auxiliary fly movable by said first mentioned fly and opposite thereto for preventing sheets deposited on the table from following the first mentioned fly on its return movement.

8. An attachment for printing presses 130

comprising an oscillating auxiliary fly adapted for attachment to the printing press table and movable when a sheet is placed thereon by the main fly to prevent said sheet following said main fly in its return movement.

9. An attachment for printing presses comprising an oscillating auxiliary fly adapted for operation by the main fly and 10 acting oppositely thereto for alternately moving into position to prevent sheets following the main fly on its idle stroke and out of the way of the main fly to permit the main fly to deposit sheets upon the printing 15 press table.

10. An attachment for printing presses comprising an oscillating auxiliary fly, a shaft about which said fly is movable and means for oscillating said fly about the 20 axis of said shaft said means comprising a pivotal or swinging member attachable to the frame of the press.

11. An attachment for printing presses comprising an oscillating auxiliary fly, a shaft about which said fly is movable and means for oscillating said fly about the axis 25 of said shaft said means comprising a pivotal or swinging member attachable to the frame of the press in position to be operated 30 by said main fly in its movement.

12. An attachment for printing presses comprising an oscillating auxiliary fly, a

shaft about which said fly is movable and means for oscillating said fly about the axis 35 of said shaft said means comprising a pivotal or swinging member attachable to the frame of the press.

13. In a printing press, the combination of tapes, a table, a fly for lifting sheets from the tapes and depositing them on the table, 40 and means secured alongside said table for preventing the sheets deposited on the table from following the fly on its return movement, said means being movable lengthwise of the table to desired adjusted position. 45

14. In a printing press, the combination of tapes, a table, a fly for lifting printed sheets from the tapes and depositing them on the table, and means secured alongside 50 said table, shiftable lengthwise thereof and controlled by said fly for preventing sheets deposited on the table from following the fly on its return movement.

15. In a printing press, the combination of tapes, a table, a main fly for lifting sheets 55 from the tapes and depositing them on the table, an auxiliary fly oscillating in timed relation with the main fly for preventing deposited sheets returning with the main fly, said auxiliary fly being secured alongside 60 the table into desired adjusted position.

EVERT E. BOBBIT.
